UNITED STATES PATENT OFFICE.

GEORGE OLDHAM, OF PHILADELPHIA, PENNSYLVANIA.

DESIGN FOR A JACK-LEVER.

SPECIFICATION forming part of Design No. 27,779, dated October 26, 1897.

Application filed July 28, 1897. Serial No. 646,270. Term of patent 7 years.

To all whom it may concern:

Be it known that I, GEORGE OLDHAM, a citizen of the United States, residing at Philadelphia, in the county of Philadelphia and State of Pennsylvania, have invented a new and original Design for Jack-Levers for Shedding-Motion Machines, of which the following is a full, clear, and exact description, the leading features of the design being fully set forth in the following specification and illustrated in the accompanying drawings.

Figure 1 is a side elevation of a witch jack-lever embodying the features of my new design. Figs. 2, 3, and 4 are cross-sectional views on the lines 2 2, 3 3, and 4 4, respectively, showing the shape of the witch in cross-section.

Fig. 1 of the drawings herewith shows an L-shaped lever, both of the integral vertical and horizontal arms of which are each pro-

vided with notches *d* upon their inner edges or faces. An open-mouthed bearing-slot is located in the heel of the L-shaped lever. A rib *c*, having a projection *c'* of similar contour, arches and integrally connects the arms or members *a*. The arc of this connection is radial from the pivotal point in the slot *b*. Projecting from the face and centrally of the notched vertical arm *a* is a boss *a'*. Surrounding the opening *b* is a projecting boss *e*.

I claim—

The design for a jack-lever herein shown and described.

In testimony whereof I affix my signature in presence of two witnesses.

GEORGE OLDHAM.
